UNITED STATES PATENT OFFICE.

EDWARD F. COGAN AND JOHN L. SBARBARO, OF DENVER, COLORADO.

DESIGN FOR A PATRIOTIC EMBLEM.

52,637.

Specification for Design.

Patented Nov. 12, 1918.

Application filed May 28, 1918. Serial No. 237,155. Term of patent 3½ years.

To all whom it may concern:

Be it known that we, EDWARD F. COGAN and JOHN L. SBARBARO, citizens of the United States, residing at the city and county of Denver and State of Colorado, have invented a new, original, and ornamental Design for a Patriotic Emblem, of which the following is a specification, reference being had to the accompanying drawing, forming a part thereof.

The figure is a front view or elevation of an article showing our new design.

We claim:

The ornamental design for a patriotic emblem, as shown.

In testimony whereof we affix our signatures.

EDWARD F. COGAN.
JOHN L. SBARBARO.

Copies of this patent may be obtained for five cents each, by addressing the "Commissioner of Patents, Washington, D. C."
